Domestic Boiler.

Patented Mar. 7. 1815.

March 1 1813
2278X
Peter Tammes
Tammes Patent

The schedule referred to on these Letters Patent and making part of
the same containing a description in the words of the said Peter Tammes
concerning himself of his mode of constructing Furnaces & Stove pipes.

The bottom of the unipressed furnace is in the form of a shallow bowl without
iron grating, in the centre over an ash pit, with suitable stones above & be-
low the grating, the boiler is suspended in these or more pillars of cast iron
brick or suitable stone, leaving a hollow space around the pillars be-
tween the bottom of the furnace & the boiler, extending under the whole
bottom of the boiler. The inner wall of the furnace is then raised with
brick or suitable stone up the sides of the boiler concentric with them with
surrounding ^{the same} at the distance of about one inch leaving a space all around
the boiler of one inch for the passage of the heat & flame in its ascent &
is not to come in contact with the boiler. The sides thus surrounding
the boiler are raised nearly to the top about four inches thick, thus
forming an inner or partition wall. Another wall of brick is then raised
so as to surround the first at the distance of about three inches in
all parts leaving a space of about 3 inches between the first described
partition wall & the outer wall of the furnace. Over the whole is a top
of thin stone or brick, fitting close & tight to the boiler & the outward
wall & resting on piers on the inner wall so as to have communica-
tion for the passage of the flame & smoke between the inner & outer in-
ner space except about one third round the boiler near the fire
not a chimney where the communication is cut off by carrying
the inner partition up to the cover. The cover can at any time be remo-
ved so as to sweep or cleanse the passage when foul. A chimney or
funnel is to be erected on one side so as to communicate with the out-
side of the cylinder near the space to carry off the smoke. The effect
of this furnace is that when the fire is placed on the grates the flame
and heat ascend without obstructing, either the bottom & up the sides,

2278

of the boiler to which they are closely applied & forming equality and
the surface being to the top of the furnace & then passing the intersections
in the top of the partition wall descending through the other spaces
on the other side of the same partition & passing the whole face of the
boiler on the boiler & partition & is carried off by the chimney & divide
of heat, the partition wall is thus heated by the flame ascending,
on one side & descending on the other & by the evolution of the external
cold air which has a long time & communicates a continuall &
uniform heat to the boiler after the fire is extinguished. (The prin-
ciple of this improvement or invention is to confine & spread the heat
uniformly over the greatest portion possible of the boiler & to retain
it in contact or in the cavities of the furnace till consumed there-
by making the operation shorter & more effectual with a great
saving of fuel.) The advantages of this improvement in the fur-
nace are great saving of fuel & labour, the preservation of the boil-
er, security from accident by fire & by the uniform distribution
of heat when thus applied to mills - an improvement in the qual-
ity of the spirits produced. This method of constructing furnaces
is equally applicable to tanks used for steam engines both horizon-
tal & perpendicular. It is particularly adapted to Carboles &
& copper on board of Ships & vessels. It is also applicable to ovens
which may be heated in this manner with great conven-
ience & effect.
